ELECTRIC FURNACE WATER HEATER

Walter E. Hudson, East Setauket, N. Y.

Application August 25, 1943, Serial No. 499,969

19 Claims. (Cl. 219—39)

This invention relates to water heaters and particularly to electric water heaters for domestic use.

One object of the invention is a novel and improved heater which is characterized by its high heating efficiency and by its adaptability to quantity production at a low cost.

A further object of the invention is a novel and improved water heater which is capable of meeting a continued demand for heated water over a longer period than other heaters with which I am familiar.

A further object of the invention is a novel and improved water heater which is characterized by an upward circulation about the heating element through an elongated small area heating chamber when no demand exists for heating water and by a reversed circulation when the heater is called upon to supply heated water and with the heated water for immediate use being drawn mainly from the upper levels of the water reservoir downwardly through heating chamber.

Further objects of the invention will herein-after appear.

For a better understanding of the invention reference may be had to the accompanying drawing forming a part of this application wherein,

The drawing is a sectional view through the center of the water heater.

Referring to the drawing, I have shown my invention as embodied in a water heater embodying an elongated vertical tank 1 of suitable metal. The bottom of the tank is indicated at 2 and the tank may be supported on a floor or on other supports at its bottom edge 3. The top closure comprises an inwardly extending flange member 19. The tank walls 1, 2 and 19 may be insulated, if desired, against the transfer of heat.

Within the tank is disposed a concentrically located enclosure or sleeve 4 telescopically arranged with a heating unit and forming a water heating and circulating chamber thereabout as herein-after described. In the embodiment shown this telescoping member 4 is in the form of a cylinder or sleeve resting at its lower end on the bottom 2 of the main casing. This member 4 is provided at the bottom with a closing and locating plate 5 of suitable material, as for example, steel, this plate 5 being disposed within the lower end of the member. This member is located and anchored centrally of the main casing 1 by means of a hot water supply pipe 6 which is screw-threadedly attached to the plate 5 and passes upwardly through the bottom 2 of the main casing and centrally thereof. In order to strengthen the

central bottom structure a metallic plate 7 is disposed centrally of the bottom 2 and exteriorly thereof with the hot water supply pipe 6 being screw-threadedly attached to this plate also. This plate 7 may be brazed or otherwise fastened to the bottom 2, as for example, as indicated by the welds 8. The pipe 6 should make a water-tight joint at the opening formed in the bottom 2 at 9 so as to form a seal against the leakage of water. If desired, a similar leak-proof seal may be provided between the pipe 6 and the plates 5 and 7.

The elongated sleeve 4 is thus anchored concentrically of the main casing 1 by means of the hot water supply pipe 6 and the strengthening and anchoring plates 5 and 7. The sleeve 4 is provided with an insulating space or jacket exteriorly thereof by the provision of a jacket 10 which is fastened and sealed along the edges 11 and 12 at the bottom and lower edges thereof to the exterior surface of the sleeve. This fastening and sealing of the jacket wall 10 to the sleeve 4 may be effected in any desirable and conventional manner.

Centrally disposed with respect to the casing 1 and telescopically arranged with respect to the sleeve or partition 4, a heater casing 15 extends downwardly into the sleeve 4 with an annular water-heating chamber A of small cross-sectional area provided between the two members 4 and 15. The heater casing 15 stops short of the bottom of the casing 1 or the plate 5 to form a small chamber or auxiliary reservoir B beneath the casing 15, and extends to a point approaching the inlet end of the supply pipe 6. The sleeve 4 is provided with one or more restricted openings 17 for establishing communication between the chamber B and the main reservoir C surrounding the members 4 and 15. The area of the inlet or inlets 17 is restricted as compared with the cross-sectional area of the annular water heating chamber A for the purpose hereinafter described.

The heater casing 15 is provided at its upper end with an outwardly extending flange 18 and this flange is supported upon the annular top closure 19 projecting inwardly from the casing wall 1 at the top. For facilitating the fastening of the flange 18 to the flange 19 an annular member or ring 20 is fastened on top of and near the inner edge of the ring 19. This ring 20 may be fastened in any suitable manner, as for example, by brazing or welding. The flange 18 of the heater casing 15 rests upon this ring 20 and is fastened thereto in any suitable manner as for example by the bolts 21 passing through openings formed in

the flange 18 and screw-threadedly attached to screw-threaded recesses formed in the ring 20. As many securing bolts 21 may be provided as needed for holding the casing 15 firmly attached to the upper closure 19 of the outer casing 1 of the heater, and preferably a water tight seal is maintained between this closure.

The heater casing 15 may be provided with spring spacers 22 disposed about the exterior surface thereof so as to bear against the interior surface of the sleeve or partition 4. These spring spacers or lugs 22 function to center the heater casing within the sleeve or partition 4 and preferably the openings formed in the flange 18 of the casing 15 are larger than the bolts 21 so as to facilitate adjustment and centering of the casing with respect to the telescoping member 4 which is fixed centrally of the bottom 2 of the tank or casing 1.

The heater housing or casing 15 is provided with a readily removable electric heater unit. This heater unit comprises three insulating plates held firmly in spaced relation by a central shaft or rod 25. There is a bottom plate 26, a top plate 27 and an intermediate plate 28. The bottom plate 26 is preferably circular to conform to the cylindrical heater housing 15 and the lower end of the rod or shaft 25 is fastened in any suitable manner to the plate 26, as for example, by being provided with a head 25' embedded in the plate. The upper end of the rod 25 is provided with an exterior screw thread and the plates 27 and 28 are supported on and carried by this rod or shaft 25 by means of two pairs of nuts 29 and 30. These nuts are screwed tightly against the upper and lower surfaces of the plates so as to hold them tightly in spaced relation with the plate 27 resting upon the flange 18 of the heater casing and with a dead air space D formed between the two plates 27 and 28 and within the upper end of the heater casing. The plate 28 preferably conforms to the interior surface of the heater casing 15 so as to isolate the electric heating chamber E from the dead air space D. The plates 27 and 28 are adjusted so as to cause the bottom plate 26 to rest upon or approach the bottom 15' of the heater casing. The plate 27 is shown of the same diameter as the flange 18 and is provided with recesses 31 to accommodate the heads of the bolts 21. Preferably the plate 27 is held tightly against the flange 18 of the heater casing so as to form a substantially air-tight seal between the space D and the outside atmosphere. Any suitable means may be provided for holding the plate 27 upon and against the flange 18 and in the particular embodiment shown, I have illustrated thumb screws 32 which are screw-threadedly attached to screw-threaded openings formed in the plate 27 and similar screw-threaded openings formed in the metal ring 20, only one of these thumb screws being shown for convenience in illustration. The flange 18 is provided with openings to accommodate these thumb screws 32.

I have diagrammatically illustrated the electric heater as mounted between the plates 26 and 28 and comprising a multiplicity of coils 35 only two of which are shown but it being understood that preferably four and more, if desired, may be employed. These electric heaters 35 are electrically connected at their lower ends in pairs by suitable connections 36 disposed in slots 37 formed longitudinally of the insulating plate 26. These coils or spirals 35 may be connected with electric terminal posts 38 mounted on the plate

27 in any suitable manner, as for example, by passing uncoiled parts of the heaters 35 up through the plates 28 and 27 and through the dead air space D. In the particular embodiment shown I have illustrated these connections as rods 39 forming parts of the terminals 38 and having screw nuts 40 engaging the upper surface of the plate 27, while the lower ends of the rods 39 are provided with similar nuts 41 screw-threadedly attached to the rods and engaging the under surface of the plate 28.

The heat radiated from the heaters 35 is insulated by the plates 26 and 28 against the passage of the heat longitudinally of the heater casing 15 or housing and is forced to pass through the comparatively thin metal wall 15 of the heater housing into the annular water heating chamber A. This chamber A is elongated but is of comparatively small cross-section so that only a comparatively small body of water is heated at one time. The heating of the water in the chamber A results in the upward movement thereof into the upper part of the outer reservoir C of the casing, while the colder water passes through the restricted openings 17 into the chamber or auxiliary reservoir B and is forced upwardly into the water heating chamber A. The cold water is supplied through a pipe 42 which enters the chamber C near the bottom thereof. The dead air space formed between the members 4 and 10 functions to insulate the heated water in the chamber A against the colder water immediately surrounding the partition or sleeve. During the normal water-heating process, when no water is being withdrawn through the pipe 6, the natural circulation of the water is upwardly through the heating chamber A into the surrounding reservoir C and downwardly therethrough. However, when there is a demand for hot water the pipe 6 withdraws the water from the top of the auxiliary reservoir B and any appreciable demand of hot water results in the withdrawal of water downwardly through the chamber A. This is because the resistance to the passage of water in this direction is less than the resistance encountered by the water in passing through the restricted openings 17. The heated water thus is drawn from the top of the reservoir C where the water is hottest, then downwardly through the heating chamber A where it is further heated during its downward passage. This reverse circulation of the water through the chamber A continues as long as there is any appreciable demand of hot water through the pipe 6, and the sleeve of water being drawn through the water heating chamber A is subjected to the large heating surface 15 about the electric heating chamber E with resultant instant and quick heating to supply a long continued demand.

The outlet pipe section 6 functions, as described above, to hold the circulating sleeve 4, 10 in the central position, and also it may be adjusted up and down by means of the screw threads shown to bring the upper end of the outlet section closer to or farther from the bottom 15' of the heater casing. The particular construction, mounting and suspension of the heater casing tend to offset the effects of expansion and contraction upon changes in temperatures.

70 I claim:

1. In an electric water heater, an elongated cylindrical casing, a centrally disposed cylindrical sleeve extending upwardly from the bottom of the casing to a level near the top of the casing, said centrally disposed sleeve forming with the

side wall of the casing an annular cylindrical water reservoir thereabout, a cylindrical heater housing unit suspended from the top of the casing and extending downwardly into the central cylindrical sleeve and forming with the interior of the same an elongated annular water-heating chamber of small cross-sectional area, said housing stopping short of the bottom of the casing and forming a relatively small reservoir in the bottom of the sleeve with said water-heating chamber communicating at the top with the first-named reservoir and at the bottom with the second-named reservoir, said second-named reservoir having a restricted communication through the wall of the enclosure at a level below the lower end of the heater housing, said heater housing having at the top thereof a dead air space and having electric heater elements in the lower part of said heater housing co-extensive with the height of said water-heating chamber, a cold water inlet leading into the casing at a point near the bottom thereof, and a hot water outlet disposed centrally of the bottom of the casing and extending upwardly to a point above the level of said communicating passage and to a level slightly below the bottom of the heater housing.

2. In an electric water heater, an elongated cylindrical casing, a centrally disposed cylindrical sleeve extending upwardly from the bottom of the casing to a level near the top of the casing, said centrally disposed sleeve forming with the side wall of the casing an annular cylindrical water reservoir thereabout, a cylindrical heater housing unit suspended from the top of the casing and extending downwardly into the central cylindrical enclosure and forming with the interior of the sleeve an elongated annular water-heating chamber of small cross-sectional area, said housing stopping short of the bottom of the casing and forming a relatively small reservoir in the bottom of the sleeve with said water-heating chamber communicating at the top with the first-named reservoir and at the bottom with the second-named reservoir, said second-named reservoir having a restricted communication through the wall of the enclosure at a level below the lower end of the heater housing, said heater housing having electric heater elements in the lower part of said heater housing co-extensive with the height of said water-heating chamber, a cold water inlet leading into the casing at a point near the bottom thereof, and a hot water outlet disposed centrally of the bottom of the casing and extending upwardly to a point above the level of said communicating passage and to a level slightly below the bottom of the heater housing.

3. In an electric water heater, an elongated cylindrical casing, a centrally disposed cylindrical sleeve extending upwardly from the bottom of the casing to a level near the top of the casing, said centrally disposed enclosure forming with the side wall of the casing an annular cylindrical water reservoir thereabout, a cylindrical heater housing unit suspended from the top of the casing and extending downwardly into the central cylindrical sleeve and forming with the interior thereof an elongated annular water-heating chamber of small cross-sectional area, said housing stopping short of the bottom of the casing and forming a relatively small reservoir in the bottom of the sleeve with said water-heating chamber communicating at the top with the first-named reservoir and at the bottom with the second-named reservoir, said second-named reservoir having a restricted communication through

the wall of the enclosure at a level below the lower end of the heater housing, said heater housing having electric heater elements in the lower part of said heater housing co-extensive with the height of said water-heating chamber, a cold water inlet leading into the casing at a point near the bottom thereof, and a hot water outlet disposed centrally of the bottom of the casing and extending upwardly to a point above the level of said communicating passage and to a level slightly below the bottom of the heater housing, said centrally disposed sleeve being insulated against the transfer of heat throughout the length of the water-heating chamber.

4. In an electric water heater, an elongated cylindrical casing, a centrally disposed cylindrical sleeve extending upwardly from the bottom of the casing to a level near the top of the casing, said centrally disposed sleeve forming with the side wall of the casing an annular cylindrical water reservoir thereabout, a cylindrical heater housing unit suspended from the top of the casing and extending downwardly into the central cylindrical enclosure and forming with the interior of the sleeve an elongated annular water-heating chamber of small cross-sectional area, said housing stopping short of the bottom of the casing and forming a relatively small reservoir in the bottom of the sleeve with said water-heating chamber communicating at the top with the first-named reservoir and at the bottom with the second-named reservoir, said second-named reservoir having a restricted communication through the wall of the enclosure at a level below the lower end of the heater housing, said heater housing having electric heater elements in the lower part of said heater housing co-extensive with the height of said water-heating chamber, a cold water inlet leading into the casing at a point near the bottom thereof, and a hot water outlet disposed centrally of the bottom of the casing and extending upwardly to a point above the level of said communicating passage and to a level slightly below the bottom of the heater housing, the top of said casing comprising an inwardly extending flange with a metallic ring mounted thereon and said heater housing having an outwardly extending flange at its top resting upon and fastened to said ring.

5. In a water heater, an elongated cylindrical casing, a centrally disposed cylindrical sleeve extending upwardly from the bottom of the casing to a level near the top of the casing, said centrally disposed sleeve forming with the side wall of the casing an annular cylindrical water reservoir thereabout, a cylindrical heater housing unit suspended from the top of the casing and extending downwardly into the central cylindrical sleeve and forming with the interior of the sleeve an elongated annular water-heating chamber of small cross-sectional area, said housing stopping short of the bottom of the casing and forming a relatively small reservoir in the bottom of the sleeve with said water-heating chamber communicating at the top with the first-named reservoir and at the bottom with the second-named reservoir, said second-named reservoir having a restricted communication through the wall of the enclosure at a level below the lower end of the heater housing, a cold water inlet leading into the casing at a point near the bottom thereof, and a hot water outlet disposed centrally of the bottom of the casing and extending upwardly to a point above the level of said communicating

passage and to a level slightly below the bottom of the heater housing, the top of said casing comprising an inwardly extending flange with a metallic ring mounted thereon and said heater housing having an outwardly extending flange at its top resting upon and fastened to said ring, and a heater element separately insertable into and removable from said housing.

6. In a water-heater, an elongated cylindrical casing, a centrally disposed cylindrical sleeve extending upwardly from the bottom of the casing to a level near the top of the casing, said centrally disposed sleeve forming with the side wall of the casing an annular cylindrical water reservoir thereabout, a cylindrical heater housing unit suspended from the top of the casing and extending downwardly into the central cylindrical sleeve and forming with the interior of the sleeve an elongated annular water-heating chamber of small cross-sectional area, said housing stopping short of the bottom of the casing and forming a relatively small reservoir in the bottom of the sleeve with said water-heating chamber communicating at the top with the first-named reservoir and at the bottom with the second-named reservoir, said second-named reservoir having a restricted communication through the wall of the enclosure at a level below the lower end of the heater housing, a cold water inlet leading into the casing at a point near the bottom thereof, and a hot water outlet disposed centrally of the bottom of the casing and extending upwardly to a point above the level of said communicating passage and to a level slightly below the bottom of the heater housing, the top of said casing comprising an inwardly extending flange with a metallic ring mounted thereon and said heater housing having an outwardly extending flange at its top resting upon and fastened to said ring, and a heater element separately insertable into the removable from said housing and comprising a centrally disposed elongated rod, a bottom insulating member fastened to the lower end of the rod, an insulating member fastened to the rod intermediate its ends and at a level above the water-heating chamber and an insulating member fastened to the top of the rod and fastened to said ring independently of the fastening of said housing, said upper insulating members forming a dead air space for insulating the heating chamber against the outside atmosphere.

7. In an electric water heater, a cylindrical casing, a centrally disposed cylindrical sleeve extending upwardly from the bottom of the casing to a level near the top of the casing, said centrally disposed sleeve forming with the side wall of the casing an annular cylindrical water reservoir thereabout, a cylindrical heater housing unit suspended from the top of the casing and extending downwardly into the central cylindrical enclosure and forming with the interior of the enclosure an elongated annular water-heating chamber of small cross-sectional area, said housing stopping short of the bottom of the casing and forming a relatively small reservoir in the bottom of the enclosure with said water-heating chamber communicating at the top with the first-named reservoir and at the bottom with the second-named reservoir, said second-named reservoir having a restricted communication through the wall of the enclosure at a level below the lower end of the heater housing, said heater housing having electric heater elements in the lower part of said heater housing co-extensive with the height of said water-heating chamber, a cold

water inlet leading into the casing at a point near the bottom thereof, and a hot water outlet disposed centrally of the bottom of the casing and extending upwardly to a point above the level of said communicating passage and to a level slightly below the bottom of the heater housing, said centrally disposed enclosure being double-walled throughout the length of the water-heating chamber and containing a dead air insulating space therein.

8. A water heater of the character described comprising an elongated vertically disposed water reservoir, telescoping members centrally disposed in the reservoir and forming an elongated annular water-heating chamber thereabout of comparatively small cross-sectional area and forming an auxiliary reservoir beneath the inner of said telescoping members, said auxiliary reservoir being in direct communication with the bottom of the main reservoir through a communicating passage of restricted area as compared with the cross-sectional area of said water-heating chamber and an outlet for hot water leading from said auxiliary reservoir.

9. A water heater of the character described comprising an elongated vertically disposed water reservoir, telescoping members centrally disposed in the reservoir and forming an elongated annular water-heating chamber thereabout of comparatively small cross-sectional area and forming an auxiliary reservoir beneath the inner of said telescoping members, said auxiliary reservoir being in direct communication with the bottom of the main reservoir through a communicating passage of restricted area as compared with the cross-sectional area of said water-heating chamber and an outlet for hot water leading from said auxiliary reservoir, and extending up to a point in said auxiliary reservoir above the level of said communicating passage.

10. A water heater of the character described comprising an elongated vertically disposed water reservoir, telescoping members centrally disposed in the reservoir and forming an elongated annular water-heating chamber thereabout of comparatively small cross-sectional area and forming an auxiliary reservoir beneath the inner of said telescoping members, said auxiliary reservoir being in direct communication with the bottom of the main reservoir through a communicating passage of restricted area as compared with the cross-sectional area of said water-heating chamber and an outlet for hot water leading from said auxiliary reservoir and heating means disposed in one of said telescoping members.

11. A water heater of the character described comprising an elongated vertically disposed water reservoir, telescoping members centrally disposed in the reservoir and forming an elongated annular water-heating chamber thereabout of comparatively small cross-sectional area and forming an auxiliary reservoir beneath the inner of said telescoping members, said auxiliary reservoir being in direct communication with the bottom of the main reservoir through a communicating passage of restricted area as compared with the cross-sectional area of said water-heating chamber and an outlet for hot water leading from said auxiliary reservoir, said telescoping members containing resilient spacing means therebetween.

12. A water heater of the character described comprising an elongated vertically disposed water reservoir, telescoping members centrally disposed in the reservoir and forming an elongated

gated annular water-heating chamber thereabout of comparatively small cross-sectional area and forming an auxiliary reservoir beneath the inner of said telescoping members, said auxiliary reservoir being in direct communication with the bottom of the main reservoir through a communicating passage of restricted area as compared with the cross-sectional area of said water-heating chamber and an outlet for hot water leading from said auxiliary reservoir, an electric heating means disposed in the inner of said telescoping members so as to form an electric heating chamber therein co-extensive with the height of said water-heating chamber and said inner member having an insulating dead air space above the heating chamber.

13. A water heater of the character described comprising an elongated vertically disposed water reservoir, telescoping members centrally disposed in the reservoir and forming an elongated annular water-heating chamber thereabout of comparatively small cross-sectional area and forming an auxiliary reservoir beneath the inner of said telescoping members, said auxiliary reservoir being in direct communication with the bottom of the main reservoir through a communicating passage of restricted area as compared with the cross-sectional area of said water-heating chamber and an outlet for hot water leading from said auxiliary reservoir.

14. In a water heater, an elongated cylindrical casing, a centrally disposed cylindrical sleeve extending upwardly from the bottom of the casing to a level near the top of the casing, said centrally disposed sleeve forming with the side wall of the casing an annular cylindrical water reservoir thereabout, a cylindrical heater housing unit suspended from the top of the casing and extending downwardly into the central cylindrical sleeve and forming with the interior of the sleeve an elongated annular water-heating chamber of small cross-sectional area, said housing stopping short of the bottom of the casing and forming a relatively small reservoir in the bottom of the sleeve with said water-heating chamber communicating at the top with the first-named reservoir and at the bottom with the second-named reservoir, said second-named reservoir having a restricted communication through the wall of the enclosure at a level below the lower end of the heater housing, a cold water inlet leading into the casing at a point near the bottom thereof, and a hot water outlet disposed centrally of the bottom of the casing and extending upwardly to a point above the level of said communicating passage and to a level slightly below the bottom of the heater housing, the top of said casing comprising an inwardly extending flange with a metallic ring mounted thereon and said heater housing having an outwardly extending flange at its top resting upon and fastened to said ring, and a heater element separately insertable into and removable from said housing and comprising a centrally disposed elongated rod, a bottom insulating member fastened to the lower end of the rod, an insulating member fastened to the rod intermediate its ends and at a level above the water-heating chamber and an insulating member fastened to the top of the rod and fastened to said ring independently of the fastening of said housing, said upper insulating members forming a dead air space for insulating the heating chamber against the outside atmosphere, said upper insulating members being held in place on said rod by means of nuts

screw-threadedly engaging said rod and engaging the upper and lower surfaces of the members.

15. In a water heater, an elongated cylindrical casing, a centrally disposed cylindrical sleeve extending upwardly from the bottom of the casing to a level near the top of the casing, said centrally disposed sleeve forming with the side wall of the casing an annular cylindrical water reservoir thereabout, a cylindrical heater housing unit suspended from the top of the casing and extending downwardly into the central cylindrical sleeve and forming with the interior of the sleeve an elongated annular water-heating chamber of small cross-sectional area, said housing stopping short of the bottom of the casing and forming a relatively small reservoir in the bottom of the sleeve with said water-heating chamber communicating at the top with the first-named reservoir and at the bottom with the second-named reservoir, said second-named reservoir having a restricted communication through the wall of the enclosure at a level below the lower end of the heater housing, a cold water inlet leading into the casing at a point near the bottom thereof, and a hot water outlet disposed centrally of the bottom of the casing and extending upwardly to a point above the level of said communicating passage and to a level slightly below the bottom of the heater housing, the top of said casing comprising an inwardly extending flange with a metallic ring mounted thereon and said heater housing having an outwardly extending flange at its top resting upon and fastened to said ring, and a heater element separately insertable into and removable from said housing and comprising a centrally disposed elongated rod, a bottom insulating member fastened to the lower end of the rod, an insulating member fastened to the rod intermediate its ends and at a level above the water-heating chamber and an insulating member fastened to the top of the rod and fastened to said ring independently of the fastening of said housing, said upper insulating members forming a dead air space for insulating the heating chamber against the outside atmosphere, said lower insulating member having embedded therein cross-over terminals to which coiled electric heating units are fastened.

16. An electric water heater comprising a main casing having an opening at the top, an auxiliary casing suspended through said opening and projecting down into said main casing, said auxiliary casing being supported from the top of said main casing and a housing disposed about the auxiliary casing and forming therewith an annular heating chamber and a removable electric heating unit disposed in said auxiliary casing and independently supported upon the top of said main casing for removal thereof without removing the auxiliary casing.

17. An electric water heater comprising a main casing having an opening at the top, an auxiliary casing suspended through said opening and projecting down into said main casing, said auxiliary casing being supported from the top of said main casing and a removable electric heating unit disposed in said auxiliary casing and comprising spaced insulator plates with coiled electric heating wires suspended between the plates said electric heating unit being independently supported on the top of the main casing for removal thereof independently of the auxiliary casing.

18. A water heater of the character described comprising a vertically disposed water reservoir,

telescoping members centrally disposed in the reservoir and forming an annular water-heating chamber therebetween of comparatively small cross-sectional area and forming an auxiliary reservoir beneath the inner of said telescoping members, said auxiliary reservoir being in direct communication with the bottom of the main reservoir through a communicating passage of restricted area as compared with the cross-sectional area of said water-heating chamber and an outlet for hot water leading from said auxiliary reservoir, said annular water-heating chamber being in communication at its upper end with the upper part of the main water reservoir, the thermal circulating path of the water with the outlet closed being from the bottom of the main reservoir through the restricted passage to the auxiliary reservoir and thence through the annular heating chamber to the upper part of the main reservoir and when said hot water out- 20

let is being used to supply hot water the hot water from the top of the tank being drawn directly through the annular chamber in a reverse direction to the thermal circulation.

5 19. A water heater of the character described comprising a vertically disposed water reservoir, telescoping members disposed in the reservoir and forming an annular water heating chamber therebetween of comparatively small cross-sectional area, an auxiliary reservoir which is in communication with the bottom of said annular chamber and in communication with the bottom of the main reservoir through a communicating passage of restricted area, and an outlet for hot water leading directly from said auxiliary reservoir and drawing hot water downwardly from the top of the main reservoir through said annular water heating chamber.
